UNITED STATES PATENT OFFICE.

HARRY MATTHEWS, OF ROCHDALE, ENGLAND.

LOOM-SHUTTLE.

1,358,229.

Specification of Letters Patent.

Patented Nov. 9, 1920.

Application filed February 9, 1918. Serial No. 216,311.

To all whom it may concern:

Be it known that I, HARRY MATTHEWS, a subject of the King of Great Britain, residing at Rochdale, in the county of Lancaster, England, have invented certain new and useful Improvements in Loom-Shuttles, of which the following is a specification.

My invention relates to improvements in loom shuttles and has for its object to render such shuttles generally more efficient and reliable in operation, suitable for any kind of yarn and easier to thread, than hitherto has been the case.

I attain these objects by the shuttle illustrated in the accompanying drawings in which—

Figure 1, is a side view, Fig. 2, a plan, Fig. 3, a longitudinal section, Figs. 4 and 5, are cross sections and Figs. 6 and 7 detached plans partly in section of a shuttle constructed in accordance with my invention.

Similar letters refer to similar parts throughout the several views.

Referring to Figs. 1, 2 and 3 of annexed drawing, the delivery end of the cop cavity ends in a slot *m* in line therewith, in which is employed a fitting *n* having a slot or groove *o* through which the weft passes and a bolt *p* across the same under the influence of a spring *q*. This bolt is adapted to prevent the weft from unduly leaving the shuttle and the same being furnished with a small knob *r*, it can be readily withdrawn by the weaver to insert the weft.

In front of the said fitting, a cavity *s* is formed in the shuttle body in which are fixed vertically two pins or studs *t* and *u* one of which is cranked and the other straight, around which the weft is placed according to the tension required. Each of the said pins or studs is provided with a flexible wire guard *v* and *w* respectively driven, or secured into the side and bottom of the cavity *s* of the shuttle body, which guards prevent the weft flying off the pins on the return pick when the shuttle recoils.

The side of the shuttle is as usually formed with a nick or slot *x* preferably at an angle of 30 degrees which nick or slot diagonally crosses the threading hole *y* formed in the 50 shuttle side communicating with the cavity *s*.

At each side of the outer end of the threading hole *y* is fixed a steel pin *z* which prevents the weft cutting into same and breaking the weft and thus forms an eye for 55 the weft to pass through.

Figs. 6 and 7 show 5 different methods of obtaining different degrees of tension on the weft.

In Fig. 6, the thread marked 1 passes 60 direct from the slot of the said fitting into the threading hole *y*, the thread 2, around the pin *u* and the thread 3, around the pin *t*, and then into the threading hole *y*.

In Fig. 7, the thread marked 4, passes 65 first around pin *t* and then around pin *u* and the thread 5 first around the pin *u* and then around pin *t* into the threading hole.

I claim:

1. In a loom shuttle, a fitting having a 70 slot located in line with the cop delivery end and with sides integral, a spring controlled bolt located in said fitting across the top of said slot, a socket in one side of said slot for said bolt to fit in and means on said bolt 75 extending above the shuttle top for withdrawing said bolt, for the purpose specified.

2. In a loom shuttle, a vertical cavity in the front end thereof, two tension pins 80 driven vertically into the bottom of the cavity, and two flexible wires bearing crosswise against said tension pins one of which is driven into the side and the other into the bottom of said cavity, for the purpose 85 specified.

Signed at Manchester, this 16th day of January, 1918.

HARRY MATTHEWS.

Witnesses:

ALFRED BOSSHARDT,
M. I. BOSSHARDT.
